INVENTOR
FRANZ E. JUTH

BY Chas. E. Juth
ATTY.

UNITED STATES PATENT OFFICE.

FRANZ E. JUTH, OF SAN FRANCISCO, CALIFORNIA.

ADJUSTABLE TREE PEDESTAL.

Application filed August 10, 1921. Serial No. 491,130.

To all whom it may concern:

Be it known that I, FRANZ E. JUTH, a citizen of the United States, residing at the city and county of San Francisco and State of California, have invented new and useful Improvements in Adjustable Tree Pedestals, of which the following is a specification.

This invention relates to a supporting device, and particularly pertains to a base or pedestal for Christmas trees and the like.

It is a principal object of the present invention to provide a collapsible and adjustable base structure by which a Christmas tree might be firmly supported, said device being simple in its operation and decidedly inexpensive as to manufacturing costs.

The present invention contemplates the use of complementary separable base members, each formed with two feet, detachably secured to each other, said base members being provided with means whereby they may be assembled and interlocked to accommodate a tree having a trunk of any desired dimension.

The invention is illustrated by way of example in the accompanying drawings in which—

Fig. 1 is a view in plan showing the assembled structure with parts broken away for the sake of convenience;

Fig. 2 is a view in side elevation showing the device;

Fig. 3 is a view in plan showing the manner in which the feet are formed.

Referring more particular to the drawings, A and B indicate two base units, each of said units being composed of a foot 10 and a foot 11. These feet are all identical in configuration and are preferably formed along the lines shown in Fig. 3 and in the manner there indicated so that the device may be very economically made. The feet

10 are fitted at their large inner ends with recesses adapted to receive the hooked ends of the clamping screws, or hook bolts 12, for the purpose hereinafter described.

Adjacent these ends of the feet 10 and along one face thereof, a vertical groove 13 is formed, which groove is of sufficient width to receive the abutting end of foot 11. This end of foot 11 is connected to the side of the foot 10 and adjacent the groove 13

55 by means of the plate 19 which is secured to the foot 10 and slidably engages the

groove 20 in the foot 11, so that when the feet 10 and 11 are connected to each other the abutting end of foot 11 will be firmly seated within the groove 13. Formed 60 through the foot 11 and extending longitudinally thereof near its abutting end is a slot 14 through which the clamping screws or hook bolts 12 extend. The outer ends of these screws are fitted with wing nuts 15 by which the structure may be clamped together.

In forming the present invention a board 16 is taken and cut in two along the line 17, after which the halves of the board are 70 cut along the saw mark 18. This will provide four feet for the structure without any waste of lumber. Two of the boards may then be slotted, as indicated at 14, while the ends of the two opposite feet 75 are grooved, as at 20, and recessed to receive the hook ends of the hook bolts, which bolts are so positioned as to pass through the slots 14 when the supporting surfaces of all of the feet rest upon the ground. 80 Grooves 13 are then formed in the proper faces of feet 10, the feet 11 are then connected adjacent thereto by engagement of the plate 19 and the groove 20, and the structure is then ready for use. 85

It will be evident that the units A and B may be instantly separated by releasing the hook bolts, the feet 10 and 11 may then be taken apart due to the fact that the plate 19 is slidable in the groove 20. When the 90 device is to be used, the feet of each unit may be assembled at right angles to each other, after which the two units are disposed on the floor and arranged around the base of a tree. Attention is directed to the 95 fact that the grooves 13 are positioned some little distance from the inner ends of the feet 11, thus causing a substantially square enclosure around which the feet are arranged. The hooked end of the bolts 12 are 100 then inserted in the recesses 12^a in the feet 10. The trunk of the tree is inserted in the enclosure, and the wing nuts 15 may thereafter be tightened. This will rigidly secure the support to the tree and will insure 105 that the tree will be firmly held as long as desired.

It is obvious that various other means, such as a hinge or the like, may be employed to connect the feet 10 and 11 together, the 110 means shown being the preferred form. Likewise, the means for securing the units

together may be a simple screw secured at one end to the legs 10 and projecting through the legs 11 to receive the winged nut for adjusting the relation of the units.

5 It will thus be seen that the device here disclosed, while simple in its construction and inexpensive as to cost of material and labor, at the same time provides a neat, adjustable and collapsible support for the 10 purpose intended.

While I have shown the preferred form of my invention, it is to be understood that various changes may be made in the structure by those skilled in the art without 15 departing from the spirit of the invention.

Having thus described my invention, what I claim and desire to secure by Letters Patent is:

1. A tree pedestal comprising pairs of supporting members, the members of each pair being arranged at right angles to each other and detachably connected together, one member of each pair having a groove therein to receive the inner end of one of the members 25 of the other pair of supporting members, the latter member having a transverse groove at its inner end and located adjacent the open side of said groove of the first mentioned grooved member, and means carried by the 30 first mentioned grooved member to engage in the groove of the second mentioned grooved member, whereby to form a tree receiving socket between said pairs of members, and securing means slidably supported 35 on the second mentioned grooved members and engageable with the inner ends of the first mentioned grooved members.

2. A tree pedestal comprising pairs of supporting members, the members of each pair being arranged at right angles to each other, one member of each pair being detach-

ably connected to a member of the other pair of supporting members, one member of each pair having a recess therein adjacent its inner end and the companion member 45 having a slot adjacent its inner end and a device operable in said recess through said slot to detachably connect the companion members of each pair together.

3. A tree pedestal comprising four members arranged tangent to one circle, the side of two of the members being grooved adjacent the inner end thereof for the reception of the abutting ends of the adjacent members, the latter being slotted adjacent their 55 inner ends, means for detachably connecting the ends of the members disposed in said grooves to said members having the grooves, and means extending through said slots and engaging adjacent members for detachably 60 and adjustably connecting the last named members to those having the slots.

4. A tree pedestal comprising pairs of supporting members, the members of each pair being arranged at right angles to each other and detachably connected together, one member of each pair having a groove therein to receive the inner end of one of the members 65 of the other pair of supporting members, the latter member having a transverse groove at its inner end adjacent the groove of the first mentioned grooved member, and a device slidably carried by each of the first mentioned grooved members for detachable 70 engagement in the respective grooves of the second mentioned grooved members, and securing means slidably supported on the second mentioned grooved members and engageable with the inner ends of the first 75 mentioned grooved members.

FRANZ E. JUTH.
